Leonard Joseph Frohn, *INVENTOR*
BY *Paul J. Bowersock*, *ATTORNEY*

UNITED STATES PATENT OFFICE.

LEONARD JOSEPH FROHN, OF LYNBROOK, NEW YORK.

FEED-INTERRUPTING MECHANISM FOR PAPER-FEEDING MACHINES.

Application filed October 6, 1921. Serial No. 505,727.

To all whom it may concern:

Be it known that I, LEONARD JOSEPH FROHN, a citizen of the United States, and a resident of Lynbrook, in the county of Nassau and State of New York, have invented certain new and useful Improvements in Feed-Interrupting Mechanism for Paper-Feeding Machines, of which the following is a specification.

10 This invention relates generally to so-called paper feeding machines, designed to automatically withdraw paper sheets one at a time from a stack or pile thereof and advance the withdrawn sheets successively to 15 a printing press or a ruling machine or to some other type of machine designed to operate in one way or another upon paper sheets, with more particular reference to appurtenant mechanism for automatically rendering the withdrawing means ineffective—or otherwise preventing further withdrawals from the stack—and checking deliveries to the ruling, printing or other paper-operating machine in case sheets "stick together" 20 or for any other reason more than a single sheet at a time is withdrawn and advanced.

In an earlier application, filed August 22, 1921, Serial No. 494,285, I have shown and described a paper feeding machine, and 30 in illustrating and describing a practical and convenient embodiment of the present invention I have chosen to show the same associated with and appurtenant to the machine of my aforesaid earlier application. 35 It is to be understood, however, that the feed-interrupting mechanism of my invention may with equal efficacy be used in connection with any other known and approved type or make of feeding machine.

40 The trouble with most feed or sheet interrupting mechanisms which have come to my attention is that which grows out of the comparative thinness of a sheet of paper and the consequent difficulty of insuring the 45 transmission of appreciable movement by two superposed sheets under conditions where no movement would be transmitted by one sheet alone—this difficulty being rendered greater in inverse proportion to 50 the weight of the stock being handled. It is thought to be obvious that there can be but one principal object of an invention such as the one involved in the machine disclosed herein, and that is the production of 55 mechanism which will be reliable or dependable in the performance of its intended func-

tion, although I have also endeavored to keep clearly in mind comparative simplicity of construction and operation, ease of adjustment and the repair or replacement of 60 parts, and general adaptability to feeding machines of different types or forms.

My invention will be more readily understood by reference to the accompanying drawings, forming a part of this specification, in which I have illustrated what I consider a practical and convenient embodiment of the invention, together with such parts of a paper feeding machine as I believe necessary to be shown for a thorough 70 understanding of the operation of the appurtenant device, and in which—

Fig. 1 is a side elevation of sheet or feed interrupting mechanism embodying my invention, with a partly sectional similar view 75 of a portion of the feeding machine;

Fig. 2 is an enlarged elevation taken from the other side of the machine of what may be termed the actuating means of the interrupter;

Fig. 3 is a transverse section taken substantially on the line 3—3 of Fig. 2;

Fig. 4 is a partly sectional end elevation of Fig. 1, showing the mechanism for checking delivery of the advancing sheets;

Fig. 5 is a fragmentary sectional side view thereof, taken substantially on the line 5—5 of Fig. 4;

Fig. 6 is a similar and more amplified view of the same with the parts moved to 90 engaging or checking positions, and

Fig. 7 is a section taken substantially on the broken line 7—7 of Fig. 5.

Referring now to the drawings in detail, I have shown in Fig. 1 a suction wheel 52 95 adjustably mounted on a driven shaft 49, this wheel 52 being of the open-face cylinder type and being provided with peripheral perforations through which air is progressively drawn by means of a suction head or 100 shoe 64 held by its own weight against the inner face of the periphery of said wheel 52 and which is open to the aforesaid perforations. This head or shoe 64 is mounted at the end of a hollow arm 63 which is, in 105 turn, mounted on and which projects from a sleeve 60 on a hollow shaft or tube 57, the connections being such that air is partially exhausted from the head or shoe 64 through the hollow shaft or tube 57.

110 A stack or pile 69 of sheets of paper is shown carried by a vertically movable table

70 and adjusted thereon by means of forward gauge-bars 92 and other adjustable gauges (not shown). The top of the front edge of the stack 69 is designed to be positioned just underneath the wheel 52 whereby, when air is partially exhausted from the head or shoe 64 the top sheet of the stack will be drawn up against the periphery of the rotating wheel and, as the points of 10 suction advance progressively, rotation of said wheel will serve to withdraw the top sheet engaged thereby and advance the same to positive engagement thereof between the driven roller 128 and the gravity-positioned 15 idler roller 131. The driven roller 128 carries a series of endless tapes 129 for advancing the withdrawn sheets in succession to the ruling or other machine to which it is designed that the sheets be fed.

20 All of the foregoing parts of the feeding machine, together with the operation thereof and their connections, supports and means of actuation, are shown and described in detail in my co-pending application aforesaid, and it is therefore considered that the above brief description is sufficient. So far as the present invention is concerned, it is only necessary to know that sheets of paper are being withdrawn, one at a time, so far 25 as can be, and fed by the tape conveyor to the desired point of ultimate delivery.

The conveyor-frame of the feeding machine includes the side-bars 122 and 122', and upon these side-bars are mounted the 30 standards 160 and 163 and their opposite counterparts 160' and 163' which, in addition to their function in connection with the feeding machine proper as fully described in my aforesaid earlier application, I employ for the support of a portion of my 35 appurtenant sheet or feed interrupting mechanism. I also employ the angle-bar 167 supported from cross-rods (one of which, 161, is fragmentarily shown in Fig. 2) between the side-bars 122 and 122' at the bases 40 of the standards 160 and 163 and their opposite counterparts, to the vertical wing of this angle-bar 167 being screwed or otherwise suitably secured the vertical wing of an 45 angle-block 11 which forms part of a bracket which includes the bearing block 12 and the upwardly projecting arms 13 and 14. Into the bearing-block 12 is screwed the threaded end of a stud or axle 15 upon 50 which is rotatively mounted an amplified pulley-wheel 16, what may be termed the sheave portion of which is provided with a groove 17 for the belt 18 which passes around the tape roller 128, the remainder of 55 said pulley-wheel 16 being of substantially cylindrical contour and providing a supporting roller in a manner to be described.

At the upper ends of the arms 13 and 14 is mounted the short shaft or pin 19 upon 60 which is pivoted the bell-crank lever-arm

20 into the end of the horizontal portion of which is screwed the threaded end of a stud or axle 21. Loose upon the stud or axle 21 is a sleeve 22 having a dividing flange 23 which separates a wheel 24 fixed 70 upon said sleeve at the outer end thereof from a disc-wheel 25 loose thereon—in fact, so loose thereon that there is considerable "play", as shown in Fig. 3. The wheel 24 is very slightly less in diameter than the disc-wheel 25 and is formed to provide a weight 26 on one side thereof whereby, being loosely mounted on the stud or axle 21 it will be yieldingly held by gravity against 75 rotation. Near the end of the vertical portion of the arm 20 I have shown a screw-pin 27 passing through a suitable aperture in said arm and screwed into the vertical wing of the angle-block 11, said pin having a head 28 which provides a shoulder-stop against which the vertical portion of said arm 20 is yieldingly pressed by means of a spring 29 in compression between said arm-portion and the angle-block 11, whereby the position of the wheel 24 relative to 80 the pulley-wheel 16 below the same may be adjusted to a high degree of exactitude by turning the screw-pin 27.

Loosely mounted on the cross rod or shaft 162 between the upper ends of the standards 160 and 160' is a sleeve or collar 30 from which projects forwardly an arm or lever 31 the free end of which is designed to be located in the path of movement of each of two pins 32 and 33 mounted in and projecting from the weighted portion 26 of the wheel 24. From the sleeve or collar 30 project downwardly two arms, 34 and 35, pivoted at the end of the former being the end of a rod 36 and pivoted at the end of the latter being the end of a rod 37. Upon the tube or hollow shaft 57 is mounted a sleeve or collar valve 38 adapted through the bringing of slots into and out of registry in a common and well-known manner to 100 open and close the interior of said tube or hollow shaft to the atmosphere. This sleeve or collar valve 38 is rotated or rocked by means of an arm 39 thereon to the end of which is pivoted the other end of the rod 36. 105

The cross rod or shaft 165 between the upper ends of the standards 163 and 163' is journaled in bearings in said standards, and keyed to said shaft 165 is a collar 40 having an arm 41 at the end of which is pivoted the other end of the rod 37. Adjustably keyed on said shaft is another collar 42 from which projects an elongated finger 43 having a head 44 at the free end thereof in which is mounted a preferably 110 soft rubber knob or button 45. This finger 43 is adjusted to be positioned about midway of an advancing sheet, and is adapted to be oscillated from a position well clear of such sheet to a position in which the 115

knob or button 45 impinges upon said sheet, a guide and supporting plate 46 being suitably mounted just below the point of impact of said knob or button.

5 I have referred to a very slight difference in diameters between the wheels 24 and 25. This difference may be said to be approximately that of the thickness of a sheet of paper from stock of average weight, and it 10 will be apparent that the ratio of effective diameters may be slightly varied and adjusted to an extreme degree of nicety by means of the screw 27, the loose bearings of the wheel 25 permitting it to continue 15 to rest under its own weight on the cylindrical or roller portion of the pulley-wheel 16 while the wheel 24 is slightly raised or lowered with relation thereto. Initial adjustment is made such that a sheet 20 of paper of the thickness of those desired to be fed will pass under the idly rotating wheel 25 and also under the weight'd wheel 24, possibly barely contacting with the latter but without sufficient pressure to effect rotation of the same against the action of the weight 26. If, however, two or more sheets 25 are at the same time passed under said wheels, the increased thickness of the traveling unit will be sufficient to cause frictional 30 engagement of the wheel 24 and rotation of the same against the action of its weight, thereby causing the pins 32 and 33 to successively impinge against the lever-arm 31 and oscillate the latter in a clockwise direction (Fig. 1).

Such oscillation of this lever-arm 31 will manifestly have a two-fold effect. First, the arm 34 will be swung to reciprocate the rod 36 rearwardly, with the effect of opening the valve 38, thereby opening the interior of the tube or hollow shaft 57 to the atmosphere and thus rendering rotation of the suction wheel 52 ineffective, wherefore a sheet can no longer be picked up and with- 40 drawn from the pile or stack 69. Secondly, the arm 35 will be swung to reciprocate the rod 37 forwardly, with the effect of rocking the shaft 165 and swinging the finger 43 down until the knob or button 45 45 at the end thereof impinges against the two or more superposed sheets which have just passed under the wheels 24 and 25, clamping said sheets between said button and the plate 46 with sufficient pressure to prevent de- 50 livery thereof to the ruling or other machine to which sheets are being fed. The checked superposed sheets having been removed, the parts may be quickly and readily restored to their normal or initial relative 55 positions and effective operation of the machine renewed. It will be noted that there is no stopping and starting of the feeding machine when the feed thereof has been thus interrupted; its operation has merely 60 been rendered temporarily ineffective.

I have referred to the arm 41, to the end of which is pivoted the end of the rod 37, as projecting from the collar 40. As a matter of fact, if this connection were rigid, adjustment of the exact arc of oscillation of the finger 43 would be too difficult to insure uniformly proper impact and continued pressure of the knob or button 45 against the sheets above the plate 46. On this account, I prefer to make the connection flexible through dividing the shaft 165, as shown in Fig. 7, mounting the collar 40 at the end of one section thereof and another collar 40' at the contiguous end of the other shaft-section, the arm 41 projecting from the collar 40'. Pins 47 and 48 are passed through longitudinally slot-bores 50 and 51 (Fig. 5) in the collar 40' and screwed into the end of the collar 40, whereby the two sections of the shaft 165 70 may be rocked through a slight arc relative to and independently of each other. I have shown slidably mounted on the finger 43 a weight 53 which is initially or normally in the positon indicated in Figs. 4 and 5, where its effect is that of tending to retain said finger in its raised or inoperative position, as will be seen from Fig. 5. When the shaft 165 is rocked to depress said finger, this weight 53 will slide by gravity to the other end of said finger, as indicated in Fig. 6, whereby the weight and not the rod 37 completes the stroke of the finger, in view of the flexible pin-and-slot connection, and makes uniform and yielding the pressure of the knob or button 45 against the sheets advancement of which it is desired to arrest.

Many modifications of minor details of my improved feed interrupting mechanism 105 for paper feeding machines will doubtless readily suggest themselves to those skilled in the art to which it appertains, and I therefore do not desire to limit my invention to the specific construction herein 110 shown and described.

I claim:—

1. In a paper-feeder, a paper support, a suction feeding device to successively withdraw the top sheet only from the support, means for advancing the withdrawn sheets, and means to cut off the suction from said feeding device and to check the delivery of sheets independently of the movement of said advancing means when two or more 120 sheets are withdrawn and advanced in superposed or overlapping relationship.

2. In a paper-feeder, a paper support, a suction feed-wheel to successively withdraw the top sheet only from the support, means for advancing the withdrawn sheets, and means to cut off the suction from said feeding device and simultaneously to check the delivery of sheets independently of the movement of said advancing means when two or 130

more sheets are withdrawn and advanced in superposed or overlapping relationship.

3. In a paper-feeder, a paper support, means for successively withdrawing the top sheet only from the support, means for advancing the withdrawn sheets, and means rendered operative when two or more sheets are withdrawn and advanced in superposed or overlapping relationship to intermit the action of said withdrawing means and clamp said superposed sheets when delivered from said advancing means.

4. In a paper-feeder, a paper support, means for successively withdrawing the top sheet only from the support, means for advancing the withdrawn sheets, and means rendered operative when two or more sheets are withdrawn and advanced in superposed or overlapping relationship to intermit the action of said withdrawing means and simultaneously clamp said superposed sheets when delivered from said advancing means.

5. In a paper feeding machine, the combination, with means for supporting a stack of paper sheets, means normally operable to repeatedly engage and withdraw the top sheet only of the stack, and means for continuing advancement in succession of the withdrawn sheets, of a driven roller over which the advancing sheets are adapted to pass, an idler roller mounted above said driven roller and spaced therefrom a distance approximating the thickness of the sheets being fed, and means actuated by rotation of said idler roller for rendering operation of said engaging and withdrawing means ineffective and simultaneously checking delivery of sheets from said advancing means.

40 6. In a paper feeding machine, the combination, with means for supporting a stack of paper sheets, means normally operable to repeatedly engage and withdraw the top sheet only of the stack, and means for continuing advancement in succession of the withdrawn sheets, of a driven roller over which the advancing sheets are adapted to pass, an idler roller yieldingly and adjustably mounted above said driven roller and spaced therefrom a distance approximating the thickness of the sheets being fed, and means actuated by rotation of said idler roller for rendering operation of said engaging and withdrawing means ineffective and simultaneously checking delivery of sheets from said advancing means.

7. In a paper feeding machine, the combination, with means for supporting a stack of paper sheets, means normally operable to repeatedly engage and withdraw the top sheet only of the stack, and means for continuing advancement in succession of the withdrawn sheets, of a roller driven from a moving element of said advancing means over which the advancing sheets are adapted

to pass, an idler roller yieldingly and adjustably mounted above said driven roller and spaced therefrom a distance approximating the thickness of the sheets being fed, and means actuated by rotation of said idler roller for rendering operation of said engaging and withdrawing means ineffective and simultaneously checking delivery of sheets from said advancing means.

8. In a paper feeding machine, the combination, with means for supporting a stack of paper sheets, means normally operable to repeatedly engage and withdraw the top sheet only of the stack, and means for continuing advancement in succession of the withdrawn sheets, of a driven roller and an idler roller resting thereon between which the advancing sheets are adapted to pass, a second idler roller mounted above said driven roller and spaced therefrom a distance approximating the thickness of the sheets being fed, and means actuated by rotation of the spaced idler roller for rendering operation of said engaging and withdrawing means ineffective and simultaneously checking delivery of sheets from said advancing means.

9. In a paper feeding machine, the combination, with means for supporting a stack of paper sheets, means normally operable to repeatedly engage and withdraw the top sheet only of the stack, and means for continuing advancement in succession of the withdrawn sheets, of a roller driven from a moving element of said advancing means and an idler roller resting thereon between which rollers the advancing sheets are adapted to pass, a second idler roller yieldingly mounted above said driven roller, spaced therefrom a distance approximating the thickness of the sheets being fed and adjustable vertically independently of said first-mentioned idler roller, and means actuated by rotation of said spaced idler roller for rendering operation of said engaging and withdrawing means ineffective and simultaneously checking delivery of sheets from said advancing means.

10. In a paper feeding machine, the combination, with means for supporting a stack of paper sheets, means normally operable to repeatedly engage and withdraw the top sheet only of the stack, and means for continuing advancement in succession of the withdrawn sheets, of a driven roller over which the advancing sheets are adapted to pass, an idler roller mounted above said driven roller and spaced therefrom a distance approximating the thickness of the sheets being fed, means for yieldingly holding said idler roller against rotation in a predetermined initial position, and means actuated by rotation of said idler roller for rendering operation of said engaging and withdrawing means ineffective and simultaneously checking delivery of sheets from said advancing means.

aneously checking delivery of sheets from said advancing means.

11. In a paper feeding machine, the combination, with means for supporting a stack 5 of paper sheets, means normally operable to repeatedly engage and withdraw the top sheet only of the stack, and means for continuing advancement in succession of the withdrawn sheets, of normally inert mechanism for rendering operation of said engaging and withdrawing means ineffective, 10 normally inert mechanism for checking delivery of sheets from said advancing means, and means for simultaneously actuating 15 said mechanisms when two or more sheets are withdrawn and advanced in superposed or overlapping relationship, said last-mentioned means comprising a driven roller over which the advancing sheets are adapted 20 to pass, an idler roller mounted above said driven roller and spaced therefrom a distance approximating the thickness of the sheets being fed, means having operative connection with each of said mechanisms, 25 and means for actuating said operating means upon rotation of said idler roller.

12. In a paper feeding machine, the combination, with means for supporting a stack 30 of paper sheets, means normally operable to repeatedly engage and withdraw the top sheet only of the stack, and means for continuing advancement in succession of the withdrawn sheets, of normally inert mechanism for rendering operation of said engaging and withdrawing means ineffective, 35 normally inert mechanism for checking delivery of sheets from said advancing means, and means for simultaneously actuating said mechanisms when two or more sheets are withdrawn and advanced in superposed or overlapping relationship, said last-mentioned means comprising a driven roller over 40 which the advancing sheets are adapted to pass, an idler roller mounted above said driven roller and spaced therefrom a distance approximating the thickness of the sheets being fed, means having operative connection with each of said mechanisms, 45 and including an actuating lever, and means 50 on said idler roller for engaging and actuating said lever upon rotation of said roller.

13. In a paper feeding machine, the combination, with means for supporting a stack 55 of paper sheets, means normally operable to repeatedly engage and withdraw the top sheet only of the stack, and means for continuing advancement in succession of the withdrawn sheets, of normally inert mechanism for rendering operation of said engaging and withdrawing means ineffective, 60 normally inert mechanism for checking delivery of sheets from said advancing means, and means for simultaneously actuating said mechanisms when two or more sheets are 65 withdrawn and advanced in superposed or

overlapping relationship, said last-mentioned means comprising a driven roller over which the advancing sheets are adapted to pass, an idler roller mounted above said driven roller and adjustably spaced therefrom 70 a distance approximating the thickness of the sheets being fed, means for yieldingly holding said idler roller against rotation in a predetermined initial position, means having operative connection with each 75 of said mechanisms and including an actuating lever, and means on said idler roller for engaging and actuating said lever upon rotation of said roller.

14. In a paper feeding machine, the combination, with means for supporting a stack 80 of paper sheets, means normally operable to repeatedly engage and withdraw the top sheet only of the stack, and means for continuing advancement in succession of the withdrawn sheets, of normally inert mechanism 85 for rendering operation of said engaging and withdrawing means ineffective, normally inert mechanism for checking delivery of sheets from said advancing means, and means for simultaneously actuating said mechanisms when two or more sheets are withdrawn and advanced in superposed or overlapping relationship, said last-mentioned 90 means comprising a driven roller over which the advancing sheets are adapted to pass, an idler roller adjustably mounted above said driven roller and spaced therefrom a distance approximating the thickness of the sheets being fed, means for yieldingly 95 holding said idler roller against rotation in a predetermined initial position, a pair of levers having a common actuating lever and each having operative connection with one of said mechanisms, and means on said idler 100 roller for engaging and oscillating said actuating lever upon rotation of said roller.

15. Mechanism for controlling machines operating upon sheets or signatures having in combination, means for advancing sheets, 110 a driven roller over which the sheets are advanced, an idler roller mounted above said driven roller and spaced therefrom a distance approximating the thickness of the sheets being fed, and means actuated by the 115 rotation of said idler roller for rendering said advancing means ineffective.

16. Mechanism for controlling machines operating upon sheets or signatures having in combination, means for advancing sheets, 120 a driven roller over which the sheets are advanced, an idler roller yieldingly and adjustably mounted above said driven roller and spaced therefrom a distance approximating the thickness of the sheets being fed, 125 and means actuated by the rotation of said idler roller for rendering said advancing means ineffective.

17. Mechanism for controlling machines operating upon sheets or signatures having 130

- in combination, means for advancing sheets, a driven roller over which the sheets are advanced, and actuated by said advancing means, an idler roller yieldingly and adjustably mounted above said driven roller and spaced therefrom a distance approximating the thickness of the sheets being fed, and means actuated by the rotation of said idler roller for rendering said advancing means ineffective. 55
18. Mechanism for controlling machines operating upon sheets or signatures having in combination, means for advancing sheets, a driven roller and an idler roller between 60 which the sheets are advanced, a second idler roller mounted above said driven roller and spaced therefrom a distance approximating the thickness of the sheets being fed, and means actuated by rotation of second idler roller for rendering said advancing means ineffective. 65
19. Mechanism for controlling machines operating upon sheets or signatures having in combination, means for advancing sheets, a driven roller actuated by said advancing means and an idler roller between which the sheets are advanced, a second idler roller yieldingly mounted above said driven roller and spaced therefrom a distance approximating the thickness of the sheets being fed, means for adjusting said second idler roller vertically and independently of the first idler roller, and means actuated by rotation of second idler roller for rendering said advancing means ineffective. 70
20. Mechanism for controlling machines operating upon sheets or signatures having in combination, means for advancing sheets, a driven roller over which the advanced sheets pass, an idler roller mounted above said driven roller and spaced therefrom a distance approximating the thickness of the sheets being fed, means for yieldingly holding said idler roller in a predetermined initial position, and means actuated by rotation of said idler roller for rendering said advancing means ineffective. 75
21. Mechanism for controlling machines operating upon sheets or signatures having in combination, means for advancing sheets, a driven roller over which the advanced sheets pass, an idler roller yieldingly mounted above said driven roller and adjustably spaced therefrom a distance approximating the thickness of the sheets being fed, means for yieldingly holding said idler roller in a predetermined initial position, and means actuated by rotation of said idler roller for rendering said advancing means ineffective. 80
22. In a paper feeder, means for advancing successive sheets from a pile, a driven roller over which the sheets are advanced, an oscillatable member mounted above said driven roller and spaced therefrom a distance approximating the thickness of the sheets being fed, and means actuated by the movement of said member for rendering said advancing means ineffective. 85
23. In a paper feeder, means for advancing successive sheets from a pile, a driven roller and an idler roller between which the sheets are advanced, an oscillatable member mounted adjacent said idler roller and above said driven roller and spaced therefrom a distance approximating the thickness of the sheets being fed, and means actuated by the movement of said member for rendering said advancing means ineffective. 90
24. In a paper feeder, means for advancing successive sheets from a pile, a driven roller over which the sheets are advanced, an oscillatable member mounted above said driven roller and spaced therefrom a distance approximating the thickness of the sheets being fed, means for adjusting said member vertically with respect to said driven roller, and means actuated by the movement of said member for rendering said advancing means ineffective. 95
25. In a paper feeder, means for advancing successive sheets from a pile, a driven roller and an idler roller between which the sheets are advanced, an oscillatable member mounted adjacent said idler roller and above said driven roller and spaced therefrom a distance approximating the thickness of the sheets being fed, means for adjusting said member vertically and independently of said idler roller, and means actuated by the movement of said member for rendering said advancing means ineffective. 100

In testimony of the foregoing, I have hereunto set my hand in the presence of two witnesses.

LEONARD JOSEPH FROHN.
